EXHAUST PIPE ATTACHMENT

William C. Curphy, Montour, Iowa

Application March 3, 1945, Serial No. 580,899

2 Claims. (Cl. 98—60)

1

This invention relates generally to tractors and like vehicles and in particular to an attachment for an upright exhaust pipe for the engines on such vehicles adapted to keep moisture from entering the exhaust pipe when the vehicle is standing idle in the open.

Tractors now in general use for road construction and farm work usually have their engines provided with upright exhaust pipes which protrude upwardly through the engine hood a distance such that the exhaust gases are carried away from the tractor operator. When these tractors are left in the open with the top of the exhaust pipe left uncovered, rain, snow and the like enters the exhaust pipe and travels therethrough into the engine cylinders. As a result the cylinders, and valves operatively associated therewith, are apt to become rusted so as to reduce their service life. More important, however, is the fact that when considerable moisture becomes entrapped in the cylinders, and the engine is then started, serious injury generally results to the crank shaft or piston connecting rods. This occurs because of the relative non-compressibility of the moisture and the resultant failure of the piston to move to its normal up-stroke position. Because of this condition the connecting rod and engine shaft are either bent or broken.

In order to prevent moisture from entering into the engine cylinder it is the usual practice to cover the upper end of the exhaust pipe with canvas or an inverted tin can. However, this procedure is often neglected or forgotten by the tractor operator. As a result exhaust pipe cover attachments have been provided which are operatively associated with the engine throttle or ignition system to automatically open the exhaust pipe when the throttle is open or the ignition system closed, and to automatically close the exhaust pipe when the engine is stopped. These devices, however, are generally complicated and are a source of inconvenience in usual engine service work because of the time required for their removal from and assembly with the exhaust pipe. Further it is apparent that the exhaust pipe can be opened on any accidental opening of the throttle or closing of the ignition system as frequently occurs in the case of children playing on tractors standing idle on farms.

It is an object of this invention, therefore, to provide an improved exhaust pipe cover attachment.

A further object of this invention is to pro-

2

vide an attachment for the upright exhaust pipe of an engine which is constructed without any movable parts and adapted to keep moisture from entering the exhaust pipe when the engine is at a standstill.

Yet another object of this invention is to provide an attachment for keeping moisture from entering an upright exhaust pipe for an engine which is of a simple and inexpensive construction, positive and efficient in operation, capable of being quickly and easily installed and removed for engine-servicing purposes and which does not interfere in any way with the operation of the engine.

15 A feature of this invention is found in the provision of a cover attachment for an upright exhaust pipe, comprising a tubular body member with a reduced exhaust inlet at one end positionable above the exhaust pipe and an exhaust outlet at its opposite end in coaxial alignment with the exhaust inlet. The inlet is connected with the body member by a perforated ring member. Within the body member is a moisture deflecting member extended across the projected areas of 20 the exhaust inlet and outlet and having a downwardly sloped upper surface to contact moisture entering the body member through the exhaust outlet and to direct such moisture to a position on the deflecting member for dropping onto the connecting ring. The moisture on the connecting ring is drained through the perforations therein to the outside of the exhaust pipe.

Further objects, features and advantages of this invention will become apparent from the following description when taken in connection with the accompanying drawings in which:

Fig. 1 is a fragmentary side view of the front portion of a tractor showing one form of the attachment of this invention in assembly relation with an upright exhaust pipe for the tractor engine;

Fig. 2 is a longitudinal sectional view through the attachment shown in Fig. 1;

Fig. 3 is a sectional view taken along the line 45 3—3 in Fig. 2;

Fig. 4 is a sectional view on the line 4—4 in Fig. 2;

Fig. 5 is a side elevational view of a modified form of the invention.

Referring to the drawings there is illustrated in Fig. 1 the front portion of a tractor having an engine 10, an exhaust gas manifold 11, and an upright exhaust pipe 12 projected through the top of the engine hood 13. The exhaust pipe attachment of this invention is indicated generally

at 15 in assembly relation with the upper end 16 of the exhaust pipe 12.

One form of the exhaust pipe attachment of this invention shown in Figs. 2, 3 and 4, comprises a lower straight tube member 17 having a slotted bottom end adapted to be positioned about the upper end 16 of the exhaust pipe 12. The tube 17 is secured to the exhaust pipe by a usual clamping strap 18.

An upper bent tube or casing 19, of a circular shape in cross section, has a central portion formed with a substantially 180° bend, with such bend terminating in straight end portions 21 and 22 arranged in coaxial alignment longitudinally of the tube 19. The top end 24 of the lower straight tube 17 is positioned in a concentrically spaced relation within the lower end 21 of the bent tube 19 (Figs. 1 and 2). This spaced relation is maintained by a perforated ring member 23 which is connected between the lower end of the bent tube 19 and the top end 24 of the straight tube 17. It is seen, therefore, that the ends 24 and 21 of the tubes 17 and 19, respectively, are in an overlapped relation and with the end 21 in a spaced relation about the end 24.

The openings in the ends 21 and 22 of the bent tube 19 are of a like size and by virtue of such ends being in coaxial alignment the upper end 22 is directly above the lower end 21 so that their projected cross sectional areas, as indicated by the dot-dash lines A in Fig. 2, define a straight cylinder. The bend in the central portion of the bent tube 19 is such that the inner wall 26 thereof extends substantially across the projected areas of the ends 21 and 22. Since the top end 24 of the straight tube 17 is arranged in a spaced relation within the bottom end 21 of the tube 19, the projected cross sectional area of the tube 17, indicated by the dot-dash lines B in Fig. 2, lies within the projected areas of the ends 21 and 22 of the bent tube 19 and is completely intercepted by the inner wall 26.

In the operation of the attachment shown in Fig. 2 moisture entering the top end 22 of the bent tube 19 may either contact the outer wall 27 of the bent central section, drop directly through the open end 22 onto the connecting ring 23, or fall against the upper, downwardly sloped portion 28 of the inner wall 26, depending upon the direction in which the moisture enters the open end 22 as indicated by the arrows in Fig. 2. The moisture contacting the outer wall 27 is moved by gravity along the inner surface of this wall to the connecting ring 23. The moisture falling on the upper sloped portion 28 of the inner wall 26 is moved by gravity to the innermost surface 29 of the inner wall 26, which surface is in a substantially vertical plane extended through a part of the connecting ring 23 as clearly appears from a consideration of Figs. 2 and 3.

A part of the moisture directed to the surface 29 may drop therefrom onto that part of the connecting ring 23 which is vertically below the surface 29, while the remaining part of the moisture may follow the surface 29 and the lower sloped surface 31 of the inner wall to the connecting ring. All of the water falling or draining to the connecting ring is drained through the perforations therein to the outside of the lower straight tube 17, and in turn to the outside of the exhaust pipe 12. It is seen, therefore, that the upper sloped surface 28 constitutes a moisture deflecting member extended across the projected cross sectional area of the exhaust pipe 12 for directing water to the outside of the exhaust pipe opening.

The attachment in no way interferes with the operation of the engine 10, the lower straight tube 17 serving as an exhaust gas inlet for the bent tube 19, and the open end 22 constituting an exhaust gas outlet. Since the bent pipe 19 has a relatively smooth curvature and is of a greater diameter than the diameter of the exhaust pipe 12 a free passage of exhaust gases takes place through the attachment without the build-up of any objectionable exhaust back pressures.

The modified form of the invention shown in Fig. 5 is similar in all respects to that shown in Fig. 2 except that the bent pipe or casing 19a is formed of a plurality of independent pipe sections 32, 33 and 34 welded together in an end-to-end relation to accomplish a substantially 180° curvature in the pipe 19a while having the opposite end openings thereof in coaxial alignment. The assembly and operation of the attachment in Fig. 5 is similar in all respects to the assembly and operation of the attachment in Fig. 2, so that a further description of the modified form in Fig. 5 is believed to be unnecessary.

From a consideration of the above description it will be seen that the invention provides an attachment for the upright exhaust pipe of an engine which is of a simple and inexpensive construction, composed of a minimum number of parts adapted to be made from generally available stock material, and which is entirely free of any movable parts whereby a positive and efficient operation is assured at all times. Further, in servicing the engine 10 it is usually necessary to remove the hood 13. This is done by lifting the hood 13 upwardly over the upper end 16 of the exhaust pipe 12 as indicated at D in Fig. 1 for a lifted position of the hood. Since the attachment of this invention is secured to the exhaust pipe 12 only by the clamping member 18, it is readily removed from and assembled with the exhaust pipe as a unit so that the attachment offers but little inconvenience in engine work.

Although the invention has been described with respect to several embodiments thereof it is to be understood that it is not to be so limited since changes and modifications can be made therein which are within the full intended scope of this invention as defined by the appended claims.

I claim:

1. The combination with an upright exhaust pipe for an engine, of an attachment to keep moisture from entering the upper end of said exhaust pipe when the engine is not being operated, comprising a first upright tube member having its lower end adapted to be secured to said exhaust pipe upper end, a second upright tube member of larger diameter than said first tube having its bottom end in an overlapping relation with the top end of said first tube, means for connecting said bottom end and said top end in a concentrically spaced relation having drain openings therein, with said second tube being formed with an arcuate bend therein such that its opposite end openings are in co-axial alignment and a wall portion at said bend is extended across the projected area of said first tube, whereby moisture entering said second tube through the upper end thereof falls on the inner surface of said wall portion for gravity flow thereon to a position above a portion of said connecting means, said second tube member being of substantially the same cross sectional area over its complete length so as to provide

for an unrestricted flow of exhaust gases therethrough.

2. An attachment for an upright exhaust pipe of an engine adapted to keep moisture from entering the upper end of the exhaust pipe, comprising a tube member having opposite end openings in coaxial alignment, and a central portion of a substantially semi-circular shape, with the inner wall of said central portion being extended across the projected areas of said coaxially aligned end openings, said tube member being of substantially the same cross sectional area over its entire length to provide for an unrestricted flow of exhaust gases therethrough, an exhaust inlet for said tube member adapted to be positioned about said exhaust pipe upper end, and means supporting said exhaust inlet in a spaced relation with said exhaust pipe upper end, with said supporting means having drain openings therein.
